UNITED STATES PATENT OFFICE.

GOTTHILF ANSGARIUS BETULANDER, OF VILLASTAD, AND NILS GUNNAR PALMGREN, OF STOCKHOLM, SWEDEN, ASSIGNORS TO THE RELAY AUTOMATIC TELEPHONE COMPANY, LIMITED, OF LONDON, ENGLAND.

CIRCUIT ARRANGEMENT FOR TELEPHONE PLANTS.

Application filed March 31, 1920. Serial No. 370,095.

To all whom it may concern:

Be it known that we, GOTTHILF ANSGARIUS BETULANDER, and NILS GUNNAR PALMGREN, subjects of the King of Sweden, and residing at, respectively, Sodertorns Villastad, Sweden, and Varvsgatan 14, Stockholm, Sweden, have invented new and useful Improvements in or Relating to Circuit Arrangements for Telephone Plants, of which

10 the following is a specification.

The present invention relates to a circuit arrangement for telephone plants for selecting a free line or circuit by means of a number of test relays corresponding to the different lines or circuits, being connected in parallel in circuits which are controlled partly by means of devices whereby the corresponding line is marked as engaged, and partly by said relays in such a way, that 15 upon closure of the circuits of said relays, the relay corresponding to the first disengaged line operates and at the same time opens the circuits of the other relays.

The invention is illustrated on the accompanying drawings which show it as applied to a switching section of an automatic or semi-automatic telephone exchange. Figure 1 shows the incoming lines and Figure 2 the outgoing lines. If it be assumed that the switching section is the pre-selecting section, the lines AL_1 , AL_2 , etc., leading into the switching section consist of subscribers' lines, while the outgoing lines $F^1 L^1$, $F^1 L^2$ etc. and $F^2 L^1$, $F^2 L^2$ etc. are trunks leading to the first group selecting section. The connections between the subscribers' lines and the outgoing trunks are established in the example shown over connecting lines $M^1 L^1$, $M^1 L^2$, etc., by means of connecting relays BR, CR, DR and switching relays OR. Thus, each subscriber's line can be connected to any one of the connecting links $M^1 L^1$, $M^1 L^2$, etc., common to a group of subscribers' lines, and each connecting link can be connected to any one of a group of trunks $F^1 L$ or $F^2 L$, different connecting links having, however, access to different groups $F^1 L$, $F^2 L$ etc. of outgoing trunks in accordance with the principle of double pre-selection. By means of the relays BR the subscribers' lines may be connected

two by two to two intermediate lines $B^1 L^1$, $B^1 L^2$, or $B^2 L^1$, $B^2 L^2$ respectively, one of which $B^1 L^2$ or $B^2 L^2$ is normally connected to the corresponding link $M^1 L^1$ or $M^1 L^2$ over back contacts of the switching relay OR¹ or OR² respectively, whereas the other $B^1 L^1$ or $B^2 L^1$ can be connected to the link by energizing the corresponding switching relay OR¹ or OR² respectively. Each connecting link may therefore be connected by means of the corresponding relays BR and OR to any one of the subscribers' lines, relay OR remaining inactive when connecting to the subscribers' lines AL^2 and AL^4 but being caused to operate when connecting to AL^1 and AL^3 . In a similar way the connecting links ML may be connected to the outgoing trunks over intermediate lines CL, DL, by means of relays CR and O₁R or DR and O₂R respectively. Each group of outgoing trunks $F^1 L$ and $F^2 L$ is accessible to a plurality of groups of subscribers' lines over the corresponding links $M^1 L$, $M^2 L$ etc. Only one such group of subscribers' lines AL^1 — AL^4 is shown in the drawing. The number of lines of the different groups may of course vary according to different working conditions. Each line comprises as usual two speech wires a , b , and one test wire c .

The selection of a disengaged connecting link ML or a disengaged trunk FL is effected by means of primary testing relays VR or secondary testing relays V₁R, V₂R respectively, one such relay being provided for each of said lines, which relays are used at the same time for controlling the circuits of the corresponding connecting and switching relays. The circuits of these testing relays are carried, as shown in the drawing, partly over working contacts B¹ K¹, B² K¹, C¹ K¹, C² K¹, D¹ K¹, D² K¹ of the corresponding connecting relays, whereby the testing relay is prevented from being operated if the corresponding connecting link or trunk is engaged, and partly over cut off contacts of all preceding testing relays, counted in the order in which the lines are engaged. Thus, the circuit of the second testing relay VR² is carried over the cut off contact K² of the first testing relay VR¹, the circuit of the third testing relay (not shown) over the

contact K^a of the second relay VR^2 and the contact K^a of the first relay and so on.

Each subscriber's line is provided with a line relay AR^4 and a cut off relay UR^4 as usual in central battery systems.

The switching operation is the following:—

When the subscriber takes off his telephone, a circuit 1 is closed over the line relay, for instance, AR^4 the subscriber's line and back to earth. Relay AR^4 operates and completes circuit 2 through a group relay GR^4 common to all subscribers' lines of the group in question. If at the moment 10 all connecting links are disengaged, whereas the first outgoing trunk $F^1 L^1$ is engaged, when one of the contacts $C^1 K^1$ of the connecting relays $C^1 R^1, C^2 R^1, C^3 R^1$, is opened, a circuit 3 is completed whereby the testing 15 relays VR^1 and $V^1 R^2$ are caused to operate. At the same time a circuit 4 is closed through the relay VR^2 and the relays $V^2 R^1, V^2 R^2$, but the circuit is opened immediately 20 after at a contact K^2 of the relay VR^1 and therefore only the relays VR^1 and $V^1 R^2$ 25 are caused to operate, which correspond to the first mentioned, which correspond to the first disengaged lines, can keep their armatures attracted. A circuit 5 is now closed through the relays last mentioned and 30 through the operating windings of the connecting relays $B^2 R^1$ and $C^1 R^2$, and at the same time a circuit 6 is closed through the operating winding of the switching relay $O^1 R^2$. The relays $B^2 R^1, C^1 R^2$ and 35 $O^1 R^2$ will therefore operate, thereby connecting themselves in a holding circuit 7 including the cut off relay UR^4 of the subscriber's line, the holding windings of the relays $B^2 R^1, C^1 R^2$ and $O^1 R^2$ and a 40 relay in the group selecting section (not shown). This completes the connection between the subscriber's line AL^4 and the trunk $F^1 L^2$. When the cutoff relay UR^4 operates, the line relay AR^4 is disconnected 45 whereby the circuit 2 is open and the relay GR^4 is de-energized. Owing to this fact the circuits 3, 5 and 6 are now also opened whereby the testing relays VR^1 and $V^1 R^2$ de-energize and, upon releasing their armatures, close the contacts K^2 and K^3 respectively, so that the other testing relays may 50 then be operated for the establishing of connections over other lines.

If on the other hand, a call has occurred 55 on the subscriber's line AL^4 , the circuit 5 would have been closed through the operating winding of the switching relay OR^1 whereby the relay last mentioned would have been operated to connect the subscriber's line to the connecting link $M^1 L^1$ 60 over the intermediate line $B^1 L^1$.

On a call from the subscribers' group 65 corresponding for instance to the connecting links $M^2 L^1, M^4 L^1$ etc. the switching relay OR^1 will not be operated as the group relay

CR of these groups do not close the circuit 6.

If all outgoing trunks FL are disengaged, only the testing relay corresponding to the first trunk is operated as this relay, upon operating, will disconnect all other testing 70 relays at its contact $V^1 K^2$.

It will appear from the above description that the selection of the connecting link as well as the outgoing trunk takes place 75 simultaneously and momentarily, the primary and secondary testing relays being connected in series.

What we claim is:—

1. In a telephone exchange, the combination of primary, secondary and tertiary 80 groups of lines, means for connecting any line of the primary group to any free line of the tertiary group through a free line of the secondary group giving access to such line of the tertiary group, relay means for testing the condition of one of the groups other than the primary group, means for testing the condition of the other non-primary group, and means for rendering the means 85 for testing the secondary group inoperative 90 if the lines of the tertiary group are busy.

2. In a telephone exchange, the combination of primary, secondary and tertiary 95 groups of lines, means for connecting any line of the primary group to any free line of the secondary group giving access to such line of the tertiary group, means for simultaneously testing the condition of all 100 the lines in the secondary and tertiary 100 groups and means for rendering the means for testing the secondary group inoperative if the lines of the tertiary group are busy.

3. In a telephone exchange, the combination of primary, secondary and tertiary 105 groups of lines, means for connecting any line of the primary group to any line of the secondary group, means associated with each line of the secondary group whereby 110 the condition of all the secondary lines is tested simultaneously and whereby the connections between the lines of the primary and secondary groups is controlled, means for connecting each line of the secondary group to any line of a sub-group of the 115 tertiary group, means associated with each line of the tertiary group whereby the condition of all the lines of the tertiary group is tested simultaneously and whereby the 120 connections between lines of the secondary group and itself is controlled and means whereby the means for testing the lines of the tertiary group control the circuits of the means for testing the lines of the 125 secondary group.

4. A system of electrical lines comprising primary, secondary and tertiary lines, means for connecting any primary line to any tertiary line, testing means associated 130 one with each line of the secondary group

and controlled partly by the connecting means and partly by such of the aforesaid testing means as are associated with secondary lines which have precedence of accessibility, testing means associated one with each line of the tertiary group and controlled partly by the connecting means and partly by such of the latter testing means as are associated with tertiary lines which have precedence of accessibility, and means whereby the testing means of the secondary

group control and are controlled by the testing means of the tertiary group.

In testimony that we claim the foregoing as our invention we have signed our names 15 this 10th day of March 1920.

GOTTHILF ANSGARIUS BETULANDER,
NILS GUNNAR PALMGREN.
